UNITED STATES PATENT OFFICE.

ALFRED B. PATTERSON, OF TULSA, OKLAHOMA.

LOADING PLATFORM.

Application filed October 25, 1927. Serial No. 228,595.

This invention relates to improvements in loading devices, being especially advantageous for use in connection with tank railway cars, having for an object to provide a platform so constructed and arranged with respect to a "car siding" that one or more tank cars upon such sidings may be quickly and safely loaded, the platform including in its construction movably mounted combined gates and walkways adapted to be selectively swung from closed or inoperative positions to open or operative positions with respect to the platform and the running board or rack of an adjacent tank car, hence permitting workers to readily walk from the loading platform on to a car running board whereby to remove the closure cap, make necessary adjustments and engagement of a filling spout with the tank and finally, to remove the spout and replace the cap with filling of the car.

An equally important object of the invention is to provide a platform of the character indicated having a plurality of ways in the side or guard rails thereof, each of which is equipped with individual combined gates and walkways, such members being swingably mounted upon adjacent portions of the platform for outward swinging movement at times, and adapted, when in their closed positions to serve as effectual gates or barriers for the aforesaid ways while when in open position, they will be lowered to substantially horizontal planes whereat the free or outer ends of the same will be juxtaposed with respect to the running board or loading rack of an adjacent tank car, thus permitting workers to conveniently and safely walk from the platform to said running board, the elevation of the platform substantially approximating the height of the tank car running board and consequently thereupon, eliminating the necessity of the workmen climbing on to the car frame and thence up the usual car ladder that its running board or rack might be reached.

Other objects of the invention will be quite obvious and in part pointed out hereinafter.

That the invention may be more definitely presented through this medium, it is believed well to state in a prefatory sense, that heretofore, considerable time, difficulty and risk have been entailed in the filling of railway tank cars wherein it is usual that work-

men upon the so-called loading racks span the space between the tank car to be loaded and the rack with a loose plank, one end of which rests upon a portion of the rack while the opposite end engages a part of the car running board of rack, the workmen then traversing this loose plank as may be required. Not only is an arrangement of this sort impractical in use, but further, a considerable element of risk is involved both in the traversing of the plank and in the lack of guarding for the loading rack, numbers of accidents having occurred through the usage of such an expedient, as by slipping and falling of workmen due to insecure footing from the plank and likewise, from the improperly guarded loading rack. In my improved device, a safe and secure means is provided in lieu of the makeshift aforesaid affording the workmen with a positive and stable walkway whereby ready and convenient access may be had to the running boards or racks of tank cars and also, affording, with arrangement of the walkways in closed positions, an effectual gate or barrier for the individual openings in the platform or loading rack guard rails for permitting access thereto when such walkways are in horizontal positions.

In order that the invention and mode of operation may be readily understood by those skilled in the art, I have in the accompanying illustrative drawings and in the detailed following description based thereupon, set out one possible embodiment of the invention.

In these drawings:

Figure 1 is a side elevation of the improved platform having portions of the same broken away,

Figure 2 is a top plan view of the platform with portions broken away showing the arrangement of the same with respect to railroad sidings and also illustrating the manner in which the walkway is adapted to be swung into a position adjacent to the running board or rack of a tank car,

Figure 3 is an enlarged vertical section through the loading platform showing the relation of one of the walkways when in lowered position with respect to a tank car, the latter being fragmentally shown.

Figure 4 is an enlarged detail in perspective having a portion thereof broken

away, showing the construction of one of the walkways and the counter weighting means therefor,

Figure 5 is an enlarged fragmentary detail in perspective illustrating a portion of the platform and the brackets for pivotally or swingably supporting the various walkways,

Figure 6 is a fragmentary detail in perspective illustrating the modified form of counterweighting for the walkways,

Figure 7 is a transverse section therethrough taken on the line 7—7 of Figure 6 looking in the direction in which the arrows 15 point, and

Figure 8 is a fragmentary detail in end elevation illustrating a form of latching means adapted to be engaged with each of the walkways with arrangement of the 20 same in their closed or vertical positions whereby to prevent accidental outward swinging movement thereof.

Having more particular reference to the drawings, in connection with which like 25 characters of reference will designate corresponding parts throughout, the invention may be stated to comprise a platform indicated generally by the numeral 1 such platform being preferably supported at a 30 height of approximately ten feet upon trestle work indicated in its entirety by the numeral 2, the opposite ends of the platform communicating with the stairway 3 and a ladder 4 whereby ingress and egress 35 to and from the same may be effected by workmen; guide rails of a suitable height and indicated herein by the numeral 5 being fixedly mounted adjacent the opposite sides of said platform and having 40 formed therein at equal spaced intervals, a plurality of ways designated by the numeral 6.

This platform 1 and the trestle work 2 supporting it may be and preferably is, for 45 the major part, of structural steel or metal formation and the platform 1 may and preferably does have a small watch or tool house 7 arranged upon the same as is shown in Figure 1, said watch house being 50 of design and size as will suffice the requirements of the loading platform or rack constituted by the platform 1 and the trestle work 2 supporting it.

Sills 8 are bolted or otherwise positively 55 secured to metal beams 9 fixedly mounted upon the trestle work 2 and over the sills 8, planking generally indicated by the numeral 10 is secured in juxtaposed relation, supporting brackets 11 being fixed to portions of the platform super-structure adjacent the various ways 6 for pivotally receiving and supporting bracket arms 12, which in turn carry lateral supporting and bracing bars 13 fixedly receiving planks 14 60 thereupon whereby to constitute a combined

walkway and gate adjacent each of said ways 6.

With a view to providing means for facilitating swinging movement of the walkways consisting of the bracket arms 12, the bars 70 13 and the planks 14 and whereby said combined walkway and gate will be caused to automatically move to its closed position, at times, an angle metal bar 15 is secured to each of the bracket arms 12 at substantially right angles to the planking 14 and to the intermediate portion of each angle metal bar, I secure one end of a flexible cable 16, said cable passing over a guide roller 17 rotatably mounted in suitable bearings upon an appropriate portion of the platform super-structure and having a counter weighting element 18 connected to its remaining or free end for vertical movement in substantially parallelism to the supporting legs of the trestle work 2. By this arrangement, it will be understood that the combined gate and walkway hereinbefore described will be normally retained in its closed position, that is, in a position adjacent or within the particular way provided therefore in the guide rail 5 of the leading platform and consequently upon this, an effectual closure will be provided for said way, thus, avoiding possibility of accidents 95 caused by the walking or falling of workmen through said way 6. When however, it is desired to use the combined walkway and gate as a walkway, an outward thrust is imparted to the planking portion 14 thereof and this portion is pivoted upon its particular mounting 12 and permitted to swing to a substantial horizontal position; the walkway with lowering, countering the weight of the element 18 and because of this, 100 reaching the limit of its downward swinging movement with a gradualness that will 105 avoid stressing or breakage of it or of the supporting means thereof.

That means may be provided for the combined gates and walkways for holding or retaining the same in their closed or respective vertical positions against undesirable outward swinging movement, I preferably provide a form of latch means of suitable 110 or approved construction. This latch means, as shown in the Figure 8, may consist of a 115 slideable spring pressed bolt 13^a mounted in suitable brackets provided therefore upon portions of the rail 5 adjacent to the different ways 6 receiving said combined gates and walkways, designated at 13^b, the outer ends of these latches being adapted to engage with portions of angle bracket keepers 13^c secured to the corresponding side and free 120 end portion of the combined gate and walkway so that with swinging of the same to its closed or vertical position, the particular latch 13^a adjacent the same will automatically engage therewith and thereby, 125 re 130

leasably secure it in such position and against undesirable outward swinging movement. When it is desired to release the gate, the latch 13^a may of course be retracted 5 against the tension of the spring means provided therefor and at this time, the combined gates and walkways may be swung outwardly upon its pivotal mounting to a horizontal position.

10 As hereinbefore inferred, each of the ways 6 formed in the guide rails 5 of the loading platform or rack are provided with a combined gate or walkway such as hereinbefore described, these elements being normally arranged in their respective closed 15 positions whereby to lend safety to the device.

In building the platform 1 and its supporting trestle 2 including the elements of 20 super-structure hereinbefore described, it is preferable that the device shall be arranged or extend substantially parallel with and between several railway track sidings; the lengths of the various combined gates and 25 walkways being such that with lowering thereof to horizontal or substantially horizontal positions, the outer or free ends of the same will be juxtaposed with respect to the usual running board or rack 19 of a 30 tank car 20, thereby permitting workmen to quickly and safely traverse the walkway and thereby reach said rack or runing board 19 for removing the tank car cap, making necessary adjustments of the filling spout of 35 the oil or delivery apparatus usually arranged upon or adjacent the loading platform, engaging said spout in the tank car filling opening and finally, removing the spout and replacing the enclosure cap upon 40 the car.

With return of a workman to the platform 1 over the combined walkway and gate, aforesaid, the device may be caused to automatically swing to its closed position by 45 imparting a slight inward pull to the now upright or substantially upright arms 15 thereof, thereby swinging the walkway upwardly from its horizontal position under influence of the counter weight 18 attached 50 to the flexible cable 16 until said walkway assumes a vertical position between its particular way 6 and thus constitute an effectual gate or barrier therefor. Also, it will be understood that as the combined gate 55 and walkway assume vertical position within the particular way 6 therefor, the spring pressed slidble latch 13^a will automatically engage with the keeper 13^c upon the same and thus releasably yet positively 60 retain or secure the combined gate and walkway in its closed or vertical position.

While I have hereinbefore described with some degree of particularity, the loading platform or rack as being provided with 65 ways 6 in the guide rails 5, upon the oppo-

site sides thereof, it will of course be understood that these ways, if desirable may be arranged only upon one side of the platform or if not this, then the number of the ways upon one or both sides of the guard rails 70 may be increased or decreased in numbers, such as conditions or preference may dictate. It is preferably, however, that the ways 6 in the guard rails 5 be so placed that with the arrangement of tank cars upon the 75 sidings adjacent which the device is arranged, one of said ways may be arranged adjacent or opposite to the running board or rack of each of the tank cars so included in the train or trains, hence providing each 80 of said tank cars with a means of access thereto for opening, filling and closing of the same without the necessity of workmen climbing over the sides of the various cars, up the usual car ladders and on to their respective running boards or loading racks. Because of the provision of means such as those described, the filling of a number of 85 train or tank cars may be effected with a material saving of time and labor and with 90 the elimination of the major portion of the risk incident to such operation.

In the Figures 6 and 7, I have shown a slightly modified form of counterweighting for the various combined gates and walkways, the arrangement being simpler than that constituted by the counterweights 18 attached to the cables 16 passing over the various pulleys 17. In this particular embodiment of counterweighting, counterweights such as indicated by the numeral 18' are fixedly secured to the upper ends of the bars or arms 15', corresponding to the arms or bars hereinbefore identified by the numeral 15, through the medium of bolts 100 or other suitable fastening devices designated at 21. These counterweights 21 are of sufficient weight to effect an automatic inward swinging movement of the combined gates and walkways whose arms or bars 15' 105 are equipped with the same and with arrangement of said combined gate and walkway in their vertical or closed positions, the counterweights will serve to retain them in that position, hence insuring the positive 110 engagement of the spring pressed latches 13^a with the keepers 13^c provided therefor.

What I claim is:

1. A device of the character described comprising an elevated platform, guide rails for the opposite sides thereof having a plurality of equi-spaced ways formed therein, combined gates and walkways pivoted to the opposite sides of the platform adjacent each of said ways, said combined gates and walkways each consisting of bracket arms pivotally engaging adjacent portions of the platform, arms rigidly connected to said bracket arms and planks fixedly secured to said last mentioned arms, 120 125 130

other arms fixed to and arranged at substantially right angles to each of said combined gates and walkways adjacent their respective bracket arms, said combined gates and walkways being adapted at times, to be arranged in substantially horizontal positions and extended outwardly from their adjacent portions of the platform, and means connected to each of said combined gates and walkways for normally and automatically returning the same to positions between the opposite sides of their respective ways and at substantially right angles to the platform.

15 2. A tank car loading platform comprising an elevated structure, the platform being arranged at a height approximately corresponding to the height of the running board of a tank car, guard means along the opposite sides of the platform, ways of ingress and egress communicating with the platform ends, said guard means having relatively spaced ways formed therein, combined gates and walkways pivotally mounted upon portions of the platform adjacent each of said ways in the guard means, said combined gates and walkways each comprising relatively rigid and right angularly arranged pairs of arms, planks spanning certain of said arms and supported upon the same, the pivotal mounting of the combined gates and walkways being effected adjacent the joints of said pairs of relatively right angularly arranged arms, and counter weighing means for automatically returning said combined gates and walkways from outwardly extended and substantially horizontal positions to positions between their respective ways of said guard means and in substantially parallel relation to the opposite sides of said ways.

3. In combination with railway siding, an elevated platform positioned in proximity to and extending co-incidently therewith for a distance substantially approximating in length the combined lengths of a plurality of railway tank cars standing on said siding and arranged in a plane approximately corresponding to that in which the car running boards are arranged, walkways pivotally mounted upon those portions of

the platform adjacent the siding movable to horizontal and raised positions and so relatively spaced as to have individual communication with the running boards of said cars when moved to their horizontal positions, said walkways each comprising relatively rigid right angularly arranged pairs of arms, planks spanning certain of said arms and supported upon the same, the pivotal mounting of the walkways being effected adjacent the joints of said pairs of relatively right angularly arranged arms, and means carried on the platform and connected to said walkways for facilitating their pivotal movement to and movably retaining them in their respective raised positions.

4. In combination with railway sidings, an elevated platform positioned between the same and in proximity thereto, said platform extending co-incidently with the sidings for a distance substantially approximating in length the combined lengths of a plurality of railway tank cars and arranged in a plane approximately corresponding to that in which the car running boards are arranged, walkways pivotally mounted upon the opposite side portions of the platform movable to horizontal and to so raised positions and when in said horizontal positions, being extended from the platform in substantially right angular relation thereto and so relatively spaced as to have individual communication with the running boards of said cars standing upon the sidings when moved to said horizontal positions, said walkways each comprising relatively rigid and right angularly arranged pairs of arms, planks spanning certain of said arms and supported upon the same, the pivotal mounting of the walkways being effected adjacent the joints of said pairs of relatively right angularly arranged arms, and means carried by the platform and connected to each of said walkways for facilitating movement of the same to their raised positions and for movably retaining the same in such positions.

In witness whereof I have hereunto set my hand.

ALFRED B. PATTERSON.
